UNITED STATES PATENT OFFICE.

GEORGE W. HEISE, OF ELMHURST, NEW YORK, ASSIGNEE TO UNION CARBIDE & CARBON RESEARCH LABORATORIES, INC., A CORPORATION OF NEW YORK.

DRY CELL AND PROCESS OF REDUCING GASEOUS PRESSURE THEREIN.

Application filed June 30, 1921. Serial No. 481,716.

To all whom it may concern:

Be it known that I, GEORGE W. HEISE, a citizen of the United States, residing at Elmhurst, in the county of Queens and State of New York, have invented certain new and useful Improvements in Dry Cells and Processes of Reducing Gaseous Pressure Therein, of which the following is a specification.

10 This invention relates to the production of sub-atmospheric pressure in hermetically sealed dry cells. The general objects of the invention are to guard against the destructive effects of gas accumulation in such cells 15 during their storage or "shelf-life" period, and to provide an improved deferred action cell partially evacuated to secure rapid entrance of activating liquid.

It is generally accepted that the pre-service deterioration of dry cells is due in large 20 part to loss of moisture and access of oxygen to the surface of the zinc, depolarizing and accelerating local action. Heretofore, however, it has not been regarded as practicable to prevent this deterioration by providing a hermetic seal on dry cells of standard construction and reagent composition, because of the disruptive effect of pressure produced by gases generated within the cell. 25

30 In order to avoid evaporation, zinc corrosion and other detrimental actions due to the presence of electrolyte solution in stored cells having the usual non-hermetic pitch seal, a number of constructions have been devised in which the cell contains only dry 35 ingredients and is adapted to be activated by introduction of water or electrolyte solution when desired for service. A common difficulty experienced with these cells is the 40 slowness with which the activating liquid permeates the excitant paste and mix.

In accordance with my invention, the defects above referred to are avoided by the reduction of pressure in hermetically sealed 45 cells, as will be more fully explained in connection with the accompanying drawing, in which—

Fig. 1 is a vertical longitudinal section through a hermetically sealed cell,

50 Fig. 2 is a fragmentary side elevation showing the sealing means,

Fig. 3 is a vertical longitudinal section through a cell of the deferred action type, and

Fig. 4 is a top plan view of the cell shown in Fig. 3, the sealing cap being removed.

Reference numeral 1 denotes a zinc container, 2 a lining of bibulous material and 3 a mix bobbin containing a carbon rod 4. The zinc container has a marginal depression 5 to which a binding post may be attached so as to lie wholly within the outline of the container. A plastic seal 6 of the usual type is provided. This seal is non-hermetic but is sufficiently close fitting to prevent undue evaporation of moisture after the removal of the absolutely air-tight closure now to be described.

The hermetic seal comprises a cap 7, of metal or other impervious material, having a cross section corresponding to that of the container 1. The cap and container, placed with their margins in abutting relation, are secured together by means of a band 8 overlying their junction. The band 8 may be attached in any manner which will give a secure and air-tight joint, as, for example, by soldering it to both the cap and container. A tongue 9 is provided on the band 8 and is adapted to be passed through an opening 10 in key 11. When it is desired to remove the hermetic sealing cap 7, the band may be severed by engaging the tongue in the key and rotating the latter to tear the metal along the lines of the sides of the tongue extended, in a well known manner. A clip 12 may be provided on the top of cap 7 or elsewhere on the cell, for holding the key in handy position.

The cap 7 is partially evacuated and forms an expansion chamber of sufficient size to receive all the gas normally evolved, without undue rise of pressure. A suitable method of securing a reduced pressure in the cap is by introducing a small amount of alcohol through an opening 13, heating to displace the air by alcohol vapor, and sealing the opening. On cooling, a part of the alcohol liquefies and most of that remaining in the vapor phase condenses when the partial pressure of evolved gases increases, due to the diminished vapor tension of alcohol at such increased pressure. Various other substances volatile at temperatures not injurious to the cell, and having no detrimental effect on its service capacity, such as ether and carbon tetrachlorid, may be substituted for alcohol. When an inflammable

substance is used to displace the air, it may be ignited at the opening 13 and allowed to burn out so far as possible. Any suitable means may be used to protect the seal from the solvent action of the volatile material, when such protection is necessary.

A reduction of pressure may also be obtained by the use of ammonia or other substances which will react with a constituent 10 of the cell, as described and claimed in my copending application Ser. No. 481,715 filed June 30, 1921. The desired result may also be obtained by placing an imperforate cap upon the cell, heating, and sealing while the 15 air within the cell is expanded. Or the cap may be sealed on, heated to displace a portion of the air through the opening 13, and the opening then sealed. The temperature to which the cell is subjected during this 20 treatment should not greatly exceed 70° C. Suction and various other expedients for securing a partial vacuum may be adopted.

When the cell is to be put in service, the sealing cap will be disconnected as described. The service characteristics of cells so protected from the deleterious effects of loss of moisture, access of oxygen, or other causes due to incomplete isolation from the atmosphere, will be found substantially 30 equal to those of freshly prepared cells.

In Figs. 3 and 4 is illustrated a hermetically sealed cell of the general type of that shown in Figs. 1 and 2, but adapted for liquid activation. My invention is not limited to any particular arrangement for admitting liquid, and it is for purposes of description only that I show a carbon electrode 14 with an axial perforation 15, opening into spaced branch conduits 16. The 40 mix bobbin 17 is preferably encased in a cloth wrapper 18. A pulpboard spacer 19 at the base of the cell centers the bobbin. A dry paste-forming material 20 of any suitable type, preferably containing electrolyte salts, is placed in the annular space 21. The cap is sealed on the cell in the manner previously described.

Sub-atmospheric pressure may be obtained in cells of this kind by the condensation 50 of a vapor. A small quantity of a volatile material, such as ether or alcohol, is placed in the bottom of the cell. The perforated cap is sealed on and the cell dipped in hot water or otherwise subjected 55 to heat sufficient to volatilize the material. Displaced air and excess vapor escape through the perforation 13, which is then sealed. Cells of this type may be subjected without injury to temperatures considerably 60 higher than may those containing moist excitant paste. A similar result can be obtained by applying suction at 13 and sealing under reduced pressure.

A pressure considerably below atmospheric can be obtained by the condensation 65

on cooling of vapors of alcohol, ether, or the like, supplied as just described. Activation is greatly facilitated by this partially evacuated condition. When the cell is to be made ready for use, it is immersed in water or 70 electrolyte solution and the sealing cap is perforated or removed. The liquid enters through the hollow carbon electrode and rapidly diffuses throughout the mix and paste-forming material, putting the cell substantially immediately in condition to give 75 a voltage and amperage equal to the best freshly prepared cells.

Another method of securing rapid activation is to fill the cell with a water-soluble 80 gas. Dry hydrochloric acid or dry ammonia are suitable for this use. The gas may be introduced into the cell after the air has been withdrawn by suction, or a current of ammonia or hydrochloric acid 85 may be used to displace the air, suitable inlet and outlet openings being provided in the cell. The latter procedure has the advantage of avoiding work at reduced pressure. When the atmosphere of the cell 90 consists essentially of the gas, the openings are sealed.

Deferred action cells charged with water soluble gas may be activated by immersing 95 in water and breaking the seal, as previously described. As the gas instantaneously condenses by being dissolved in the water entering the cell, a partial vacuum is produced, and the mix and paste are rapidly 100 permeated by the liquid. Dry ammonia and dry hydrochloric acid are substantially inert while sealed within the cell and their presence is not objectionable after activation.

A number of liquids and gases are known 105 which would not be injurious to dry cells and which have physical properties enabling them to be used as pressure reducing agents in the manner described. The invention is accordingly not limited to the compounds 110 specifically mentioned. Various modifications of the cell structure and sealing means may also be made without exceeding the scope of the invention as defined in the appended claims. 115

I claim:

1. A hermetically sealed dry cell in which the pressure is sub-atmospheric.
2. A hermetically sealed dry cell in which the pressure is sub-atmospheric, such pressure being produced chiefly by a readily condensable vapor.
3. A dry cell having a partially evacuated sealing cap.
4. A dry cell having a sealing cap containing a readily condensable vapor in amount sufficient to materially diminish the pressure in the cap upon condensation.
5. A dry cell having an expansion chamber in which the pressure is initially less 120

than atmospheric, said chamber being adapted to receive gases evolved in the cell.

6. A hermetically sealed dry cell of the deferred action type in which the pressure is sub-atmospheric.

7. A hermetically sealed dry cell of the deferred action type containing a readily condensable aeriform fluid in amount sufficient to materially diminish the pressure in the cell upon condensation.

8. A hermetically sealed dry cell of the deferred action type in which the aeriform contents consists mainly of a readily condensable vapor.

9. A hermetically sealed dry cell of the deferred action type in which the pressure is sub-atmospheric, such pressure being produced by the vapor of alcohol.

10. The process of reducing the gaseous pressure within a hermetically sealed dry

cell, comprising displacing air with a readily volatile substance, sealing at elevated temperature, and cooling to condense a substantial portion of the volatile substance.

11. The process of preparing a dry cell of the deferred action type for rapid activation by addition of liquid, comprising producing sub-atmospheric pressure therein.

12. The process of preparing a dry cell of the deferred action type for rapid activation by addition of liquid, and activating the same when desired for use, comprising producing sub-atmospheric pressure therein, hermetically sealing the cell, immersing in liquid, and breaking the seal to permit the liquid to enter and permeate throughout the cell.

In testimony whereof, I affix my signature.

GEORGE W. HEISE.
